UNITED STATES PATENT OFFICE.

JULIUS R. BUX AND GEORGE R. OPPERMANN, OF PHILADELPHIA, PENNSYLVANIA.

DESIGN FOR TEXTILE EDGING.

43,266.

Specification for Design.

Patented Nov. 26, 1912.

Application filed September 11, 1912. Serial No. 719,890. Term of patent 14 years.

To all whom it may concern:

Be it known that we, JULIUS R. BUX and GEORGE R. OPPERMANN, both citizens of the United States, and residents of Philadelphia, in the county of Philadelphia and State of Pennsylvania, have invented a new, original, and ornamental Design for Textile Edgings, of which the following is a specification, reference being had to the accompanying drawing, forming part thereof.

The drawing illustrates a portion of textile edging showing our new design.

We claim:—

The ornamental design of a textile edging as shown.

In testimony whereof we affix our signatures, in presence of two witnesses.

JULIUS R. BUX.
GEORGE R. OPPERMANN.

Witnesses:

C. P. ALLEN, Jr.,
HARRY GILL, Jr.
